WORK SUPPORT FOR A LASTED SHOE

Frank B. Dopp, St. Louis, Mo., assignor to Perma Corporation, a corporation of Illinois

Original application October 24, 1932, Serial No. 639,221. Divided and this application September 21, 1933, Serial No. 690,307

4 Claims. (Cl. 12—123)

This is a divisional application of an application for patent filed in my name on October 24th, 1932, Serial Number 639,221.

This invention relates to a work support for supporting lasted shoes for operations upon them, such for instance, as when securing heel attaching plates to the heel seat areas of soles, heels to the heel seat areas of the soles and the like. The work support can be used in combination with a heeling machine, or independent thereof.

Objects of the invention are to provide a work support which is slidably mounted on a base, the last member of the support being mounted for movement to better positions to work thereon for the operations upon it by a heeling machine, and, to provide a device which is simple and inexpensive in construction and highly efficient for the purpose intended.

With the above and other objects in view, the invention consists in the novel features of construction, arrangement and combination of parts hereinafter more fully described and finally pointed out in the claims hereto appended.

One form which my invention may assume appears in the accompanying drawings, in which:

Fig. 1 is a view in front elevation of the machine showing my work support associated therewith.

Fig. 2 is a top plan view of the lasted shoe support mounted on a base.

Fig. 3 is a vertical sectional view of the lasted shoe support.

Fig. 4 is a view partly in sectional elevation and partly in end elevation of the lasted shoe support or jack.

Fig. 5 is a side view of heeling machine with which my work support can be used.

The reference character B designates, generally, a heeling machine having a plunger 6 adapted to carry a tool b and provided with a gauge device having adjustable counter engaging arms 35, as fully disclosed in the parent application above referred to.

A pair of suitable guides 14 are fixed on the base 1 of the machine. A suitable lasted shoe support 15 is mounted for sliding movement on the base 1 between the guides 14 so that the support can be moved toward and away from the upright 2 of the machine. When operatively positioned, the support 15 is disposed below the plunger 6 of each machine, as shown in Fig. 5. The support 15 is provided with a suitable swivelly mounted head 16 having a recess 17 open at its forward end. The lower surface of each head 16 is suitably concaved, or longitudinally and trans-

versely curved, as at 18, and the upper surface of each support 15 is suitably convexed, or longitudinally and transversely curved, as at 19.

The support 15 is provided with a suitable opening 20. The head 16 is held on the support 15 by means of a depending pin 21 insertable through the opening 20. A suitable spring 22 encircles the pin and is interposed between the apertured top of the support 15 and a stop 23 carried by the pin. The recess 17 of the head 16 is adapted to receive a part 24 of a shoe last 25 to be supported by the recessed head 16.

The gauge mechanism shown, is used for locating the shoe counter and the heel seat of a shoe in proper position relative to the plunger, 15 or ram of the machine.

In the shoe gauging operation, the operator applies foot pressure to the foot pedal 45 of the machine, thereby moving downwardly, from dotted line position in Fig. 5, the gauge arms 35, 20 into contact with the counter f' of the lasted shoe to properly locate the position of the heel seat portion f of the shoe relative to the heel plate holder b. The operator then opens the valve 10 by moving lever 11 to dotted line position, causing fluid pressure to enter the cylinder 4, thereby actuating the piston therein and forcing the plunger 6 associated therewith and the plate holder b downwardly to perform the operations desired upon the lasted shoe. After 30 the operation, the operator closes the valve 10 and the fluid pressure within the cylinder is exhausted due to the spring within the cylinder moving the plunger and plate holder to their uppermost positions. After the operation, the operator releases foot pedal and the gauge arms 35 are automatically elevated to their uppermost position, as shown in full lines in Fig. 5. The lasted shoe is then removed from the head 16 of support 15.

It is, of course, understood that the work support may be used with other types of machines, or used independently thereof, if so desired.

It will be apparent, however, from the foregoing description that due to the construction of 45 the work support, the work supported thereby will be properly positioned relative to the plunger of a machine associated therewith due to the last member being adjustably mounted relative to the support therefor.

What I claim is:

1. In a jack for supporting lasted shoes, a hollow base member, a convexed face at the upper end of said base, a head member having a recess in the upper face thereof and open at one 55

end to receive the neck end of a shoe last, said head having its lower face concaved to conform to the convexed face of the base member and mounted thereon and yieldable connecting means 5 to permit swivel movement of the head upon the base member.

2. In a jack for supporting lasted shoes, a hollow base member, a convexed face at the upper end of said base, a head member having a recess in the upper face thereof and open at one end to receive the neck end of a shoe last, said head having its lower face concaved to conform to the convexed face of the base member and mounted thereon, a post depending from 10 the head member directed through a suitable opening in the upper end of the base member, a stop member carried by the post and suitable resilient means encircling the post between the upper end of the base member and the stop on 15 said post.

3. In a jack for supporting lasted shoes, a base member having a suitable longitudinally curved upper face merging with a relatively narrow transversely curved face, a head member having a correspondingly curved lower face mounted on the upper face of the base member for arcuate sliding movement thereon and longitudinally and transversely thereof, said head member having a recess open at one end and having a plane base surface, and means frictionally 20 connecting the two members. 5

4. In a work support, a base member having a vertically disposed tapered opening, a last bed plate swivelly mounted on the base member and having a plane last engaging surface bounded 15 except for one end thereof with a flange, a pin depending from the last bed plate, a thrust plate on the pin and a coiled spring encircling the pin between the base member and the thrust plate. 10

FRANK B. DOPP. 20
